PRECAST FLOOR OR ROOF SLAB

Filed Sept. 21, 1933

UNITED STATES PATENT OFFICE

1,990,157

PRECAST FLOOR OR ROOF SLAB

Howard F. Young, Kalamazoo, Mich.; Leonie S.
Young administratrix of said Howard F. Young,
deceased

Application September 21, 1933, Serial No. 690,299

13 Claims. (Cl. 72—68)

This application is a continuation in part of my application Serial No. 641,362 filed November 5, 1932, for pre-cast floor or roof slabs. The invention relates to those of my co-pending applications Serial No. 532,835 filed April 25, 1931 and Serial No. 532,837 filed April 25, 1931. The invention has for its objects:

First, to provide a simple and effective concrete or cement floor or roof construction in which 10 pre-cast joists and pre-cast slabs are utilized.

Second, to provide such a construction in which the slabs and joists are joined together with a cement-to-cement bond to form a monolith without the use of any projecting steel or 15 other reinforcements to act as bonding members.

Third, to provide such a construction that may be easily, cheaply and quickly put up and in which the parts may be made away from the building site, which greatly reduces the cost.

Fourth, to provide such a floor or roof in which pre-cast joists and slabs are joined together with a cement-to-cement bond to provide T-beam construction in which the pre-cast slabs act as compression members.

Fifth, to provide a pre-cast slab of concrete or similar material of suitable form to be joined to other slabs and to joists.

Other objects and advantages pertaining to details of construction will appear from the description to follow. A preferred embodiment of my invention is illustrated in the accompanying drawing, in which:

Fig. 1 is an isometric fragmentary perspective view of a floor or roof made in accordance with my invention, showing the steps during construction and a portion in substantially finished form, a portion of the finishing mortar being broken away to show disposition and arrangement of the various parts.

Fig. 2 is a detail transverse section through one of the joists and the floor showing the arrangement of the slabs and the bonding between the slabs and the joists.

Fig. 3 is a section through a portion of the floor parallel to a joist showing the arrangement of the slabs and the finishing mortar.

Fig. 4 is a similar view showing a slightly modified type of slab.

Fig. 5 is a detail view partly in section taken transversely through a girder and through one of the joists showing the continuity obtained by my invention.

The parts will be identified by their numerals of reference which are the same in all the views.

1 indicates a pre-cast joist made in accordance

with my co-pending application Serial No. 532,837, filed April 25, 1931. This joist comprises a joist pre-cast from concrete and reinforced by metal reinforcements. The concrete is preferably what is known as porous concrete which may be made with a gravel aggregate or an aggregate of vitrified, aerated clay or cinder or any product known commercially as a light weight aggregate. The use of ordinary concrete with a usual gravel aggregate is equally possible, and has only the possible disadvantage of increased weight.

2 is a longitudinal reinforcing bar and 3 are tension reinforcing bars of suitable metal. 4 are metal shear members. The members 2, 3 and 4 may be welded in the positions shown in Fig. 1. 5 are pre-cast concrete slabs that are preferably approximately twelve inches wide, from one to two inches thick and ten feet in length. These dimensions need not necessarily be followed but are a suitable size for easy handling.

6 are longitudinal metallic reinforcing bars in said slabs. The slabs can be reinforced by any suitable mesh or other reinforcing as desired. The edges of the slabs are beveled as at 8 or may be shouldered as at 9 (see Fig. 4) to provide a recess between the slabs for the reception of bonding cement. Any suitable shaping to form such a recess can be used. The slabs 5 are disposed over and transversely of the joists 1, as shown, and are joined thereto by a cement bond 10 which may be buttered on the heads of the joists or may be applied in any suitable way. It is possible to place the slabs on the joists and trowel or spray the cement to form a shoulder 11 which embraces the sides of the heads of the joist 1 and the under side of the slab to form a complete bonding of considerable section as necessary.

12 are reinforcing metallic rods disposed transversely of the slabs for reinforcing and load distributing and also to prevent shrinkage. In some constructions it is desirable to place negative reinforcing members 13 across the slabs as shown in Fig. 5. These rods 13 are disposed across girders or wall supports and when bonded in position provide cantilever support for the construction and produce continuity as will be explained. Such negative reinforcing rods are not necessary in all constructions, but are desirable where an especially strong construction is desired.

14 is a finishing mortar coat overlying the slabs and embracing the rods 12 and 13, also running into the recesses between the slabs to bond the

slabs to one another and to bind the whole together to form a monolith. In such constructions it has been found desirable to put a grouting in the groove between the slabs to bind them together before any finishing coat is put on the slabs or before the rods 12 and 13 are placed. After the mortar has been placed between the slabs, it is allowed to set and the floor or roof formed is sufficiently strong to permit its use. 10 15 are wood sleepers that may be installed in the coating 14 if it is desired to lay a wood floor, such as 16, thereover.

It will be easily understood that the mortar 10 binds the slabs 5 to the joists 1 to form a cement-to-cement bond that is of considerable strength and which binds the slabs to the joists to give a T-beam effect. The mortar 14 running into the recess between the slabs, or the grouting placed between the slabs before pouring the finishing layer, binds them together with a cement-to-cement bond. The mortar 14 binds the rods 12 and 13 to the slabs. The whole construction is then monolithic in its nature.

I have described the construction as of concrete and I do not wish to be limited to ordinary Portland cement concrete by use of the term cement. Any cementitious material, such as gypsum or the like, could be used.

I have described the use of a light weight aggregate to produce a porous construction, and although this is the preferred form, tests have shown that any form of concrete having what is termed absorptive qualities could be used, or any type of cement that can be bonded with a cement-to-cement bond. Although it is most desirable that the cementitious material used in the joists, the slabs and the mortar be substantially similar, it is possible to bond certain dissimilar cements together and I do not wish to be confined to the use of similar cementitious material at all times.

By using the negative reinforcing rods 13, it is possible to obtain cantilever support over girders or wall supports and the bonding of the cement to the joists and the other parts produces what is known as continuity. The bar 13 or, to a certain extent, even the bars 12 become tension members when stretched over a support. The tension is transferred from the rod 13 to the tension member 3 of the joist by the shear members 4 and the concrete bonding, thus providing for tension of the supports as it is needed, running continuously through the tension of the joists. In such a construction the girder is preferably poured to embrace the end of the joist and may be integral with the covering 14, as is illustrated in Fig. 5.

It has heretofore been thought that a bonding such as I have described between the joists and the slabs and between the adjacent slabs could not be utilized, and constructions attempting to use pre-cast concrete members have provided metal extensions to be cast in cement to provide for bonding. By using my construction it is unnecessary to provide such members, and I am able to obtain a complete monolith in which the slab becomes the compression member in a T-beam construction. This is accomplished with a saving of reinforcing material and with a saving of labor in arranging for the projecting reinforcements, which also greatly facilitates handling the concrete slabs and joists.

After the coating 14 is poured or spread on the tops of the slabs and embracing the rods 12, the ends of the slabs are held up by the load dis-

tributing reinforcing rods 12 and the bond formed between the coating and the slabs.

It is possible to use this slab on steel or other suitable joists. This would give a completely monolithic slab as can be formed with a poured slab over steel joists.

Having thus described my invention, what I claim as new and desire to secure by Letters Patent is:

1. A concrete floor or roof formed with pre-cast concrete joists having longitudinal reinforcing tension members cast therein and having wall or girder supports, with the abutting ends of the joists joined by a cement-to-cement bond, pre-cast reinforced concrete slabs overlying said joists and united thereto and to one another by a cement-to-cement bond, shrinkage and slab reinforcing rods overlying said slabs transversely, negative reinforcing rods extending transversely of said supports, a concrete mortar top finishing overlying said slabs and embracing said rods whereby said rods are bound to said slabs and whereby said negative reinforcing rods provide cantilever support. 10 15

2. A concrete floor or roof formed with pre-cast concrete joists having longitudinal reinforcing tension members cast therein and having wall or girder supports, with the abutting ends of the joists joined by a cement-to-cement bond, pre-cast concrete slabs overlying said joists and united thereto and to one another by a cement-to-cement bond, shrinkage and slab reinforcing rods overlying said slabs transversely, a concrete mortar top finishing overlying said slabs and embracing said rods whereby said rods are bound to said slabs. 30

3. A concrete floor or roof formed with pre-cast concrete joists, pre-cast reinforced concrete slabs overlying said joists and united thereto and to one another by a cement-to-cement bond, shrinkage and slab reinforcing rods overlying said slabs transversely, a concrete mortar top finishing overlying said slabs and providing a cement-to-cement bond between said slabs and embracing said rods whereby said rods are bound to said slabs to provide continuity, whereby a monolith is formed. 40 45

4. A concrete floor or roof formed with pre-cast concrete joists, pre-cast concrete slabs overlying said joists and united thereto and to one another by a cement-to-cement bond, shrinkage and slab reinforcing rods overlying said slabs transversely, a concrete mortar top finishing overlying said slabs and embracing said rods whereby said rods are bound to said slabs to provide continuity, whereby a monolith is formed. 50 55

5. A concrete floor or roof formed with pre-cast concrete joists, pre-cast reinforced concrete slabs overlying said joists and united thereto at their contacting surfaces with a mortar joint forming a cement-to-cement bond, said slabs having their abutting edges whose direction extends transversely to the direction of the joists joined with a mortar joint forming a cement to cement bond, and a concrete mortar top finishing overlying said slabs whereby a T-beam monolith without projecting metallic reinforcement penetrating the joints between the pre-cast members is formed in which the slabs form the principal compression member and the joists the principal tension members. 60 65 70

6. A concrete floor or roof formed with pre-cast concrete joists, precast concrete slabs overlying said joists and united thereto at their con- 75

tacting surfaces with a mortar joint forming a cement-to-cement bond, said slabs having their abutting edges whose direction extends transversely to the direction of the joists joined with a mortar joint forming a cement to cement bond, a concrete mortar top finishing overlying said slabs, whereby a T-beam monolith without projecting metallic reinforcement penetrating the joints between the pre-cast members is formed in which the slabs form the principal compression member and the joists the principal tension members.

7. A concrete floor or roof formed with pre-cast concrete joists, pre-cast reinforced concrete slabs overlying said joists and united thereto at their contacting surfaces with a mortar joint forming a cement-to-cement bond said slabs having their abutting edges whose direction extends transversely to the direction of the joists joined with a mortar joint forming a cement to cement bond, whereby a T-beam monolith without projecting metallic reinforcement penetrating the joints between the pre-cast members is formed in which the slabs form the principal compression member and the joists the principal tension members.

8. A floor or roof formed with joists pre-cast from a cementitious material, slabs pre-cast from cementitious material, and overlying said joists and united thereto at their contacting surfaces by a mortar comprising a cementitious material to form a T-beam monolith without a projecting metal reinforcement penetrating the joints between the pre-cast members and in which the slabs form the principal compression member and the joists the principal tension members.

9. A floor or roof formed with joists pre-cast from cementitious material, slabs pre-cast from cementitious material and overlying said joists and united to each other by a cement mortar, and united to said joists at their contacting surfaces by a cement mortar embracing the heads of said joists to form a T-beam monolith in which the slabs form the principal compression mem-

ber and the joists the principal tension members.

10. A floor or roof formed with pre-cast concrete joists, pre-cast concrete slabs overlying said joists and united to each other by a cement mortar and united to said joists at their contacting surfaces by a cement mortar embracing the heads of said joists to form a T-beam monolith in which the slabs form the principal compression member and the joists the principal tension members.

11. A concrete floor or roof structure formed with pre-cast concrete joists and pre-cast concrete slabs overlying said joists and united thereto at their contacting surfaces solely with a mortar joint forming a cement to cement bond, said slabs having their abutting edges whose direction extends transversely to the direction of the joists joined solely with a mortar joint forming a cement to cement bond to form a T-beam monolith in which the slabs form the principal compression member and the joists the principal tension members.

12. A concrete floor or roof structure formed with pre-cast concrete joists and pre-cast concrete slabs overlying said joists and united thereto at their contacting surfaces solely with a mortar joint forming a cement to cement bond to form a T-beam monolith in which the slabs form the principal compression member and the joists the principal tension members.

13. A concrete floor or roof structure formed with pre-cast concrete joists and pre-cast concrete slabs overlying said joists and united thereto at their contacting surfaces with a mortar joint forming a cement to cement bond, said slabs lying in staggered relation and having their edges whose direction extends transversely of the direction of the joists abutting and joined by a mortar joint forming a cement to cement bond to form a T-beam monolith in which the slabs form the principal compression member and the joists the principal tension members.

HOWARD F. YOUNG.
